ELEVATOR

Albert M. Best, New Holland, Pa., assignor to The Sperry Corporation, New Holland, Pa., a corporation of Delaware

Application March 31, 1953, Serial No. 345,833

7 Claims. (Cl. 198—104)

1

This invention relates to elevators of the type generally exemplified in the United States Patent to Hancock No. 1,746,649 granted February 11, 1930.

In such elevators it has been customary to utilize a suitable lateral conveyor such as an auger to deliver the conveyed material to an endless elevating conveyor having a series of relatively spaced conveyor flights or buckets thereon to receive the material and carry it upwardly to the delivery end of said elevator conveyor. In conveyors of this type difficulty has been encountered in transferring the material from the lateral conveyor to the elevator conveyor due to the tendency of the material to jam up at the transfer joint. Such jamming up has not only decreased the efficiency of the elevator but has frequently resulted in damaging the flights of the elevator conveyor.

It is, accordingly, a primary object of the present invention to resolve this difficulty by providing a rotary feed element for receiving the material from the lateral conveyor and efficiently delivering it without jamming to the elevator conveyor, the rotary element having feed paddles which rotate therewith in timed relation to the auger flights so that their adjoining paths of movement are in non-registering relation and the paddles will accordingly tend to deliver the material between the respective conveyor flights without damage to such flights. To this end the rotary feed element is operatively connected to the conveyor for movement in timed coordinated relation therewith.

It is further an important object of the invention to provide a disengageable coupling in the drive mechanism for the rotary feed element, the coupling being operable to engage and cause rotation of the feed element only in the relatively coordinated positions of said feed element and the vertical or elevator conveyor.

Further objects and advantages will be apparent from the following description considered in conjunction with the accompanying drawings in which:

Figure 1 represents a view in elevation and partly in section along the line 1—1 of Figure 3, a portion of the elevator mechanism being broken away;

Figure 2, a vertical section on the line 2—2 of Figure 1, looking in the direction of the arrows, portions of the structure being broken away;

Figure 3, a plan section on the line 3—3 of Figure 1, portions being broken away; and,

Figure 4, a view on the line 4—4 of Figure 2 looking in the direction of the arrows and showing the details of one of the clutch members.

Referring now in detail to the accompanying drawings, the reference characters 2 therein respectively designate relatively spaced horizontal channel irons which define a supporting base for an elevator casing or housing 3 within which operates a usual endless conveyor 4 having rela-

2

tively uniformly spaced conveyor flights 5 carried thereon. The conveyor 4 which in the present instance is in the form of a usual sprocket chain is guided around sprockets 6 and 7 respectively supported for rotation at the upper and lower ends of the housing 3. As is best shown in Figure 3, the shaft 8 which supports the lower sprocket 7 is journaled across the housing 3 and has a pulley 9 keyed thereon exteriorly of housing 3. This pulley 9 is driven in conventional manner by a belt 10 from a conventional electric motor 11 supported on the base members 2—2. A generally U-shaped partition 12 extending over the shaft 13 of the upper sprockets with its legs 14 depending vertically on opposite sides of the shafts 8 and 13 divides the housing 3 interiorly into an elevating leg or passage 14 and a return passage 15 through which the runs of the conveyor 4 move in opposite directions in well known manner. The shaft 13 above mentioned is rotatably journaled across the upper part of housing 3 to support the sprocket 6.

The motor 11 rotates the shaft 8 in a counter-clockwise direction as viewed in Figure 1 so that material fed into the lower end or boot 16 of the elevator is carried by the conveyor flights 5 upwardly through the elevator passage 14 and discharged over the upper end of the conveyor through a discharge spout 17.

25 A generally cylindrical feeder housing 18 communicates laterally with the interior of the boot 16 through an opening or port 19 communicating preferably with the return passage 15 in radially spaced relation to the sprocket wheel 7 or other 30 rotary element around which is guided the lower end of the elevator conveyor 4. Rotatably supported through one axial end of the feed housing 18 in a bearing 20 is a horizontal shaft 21 parallel to the shaft 8. Fixed on this shaft 21 35 within the feed housing 18 is a rotary feed element including a plurality of uniformly circumferentially spaced feed paddles 22, each projecting in a generally radial direction from their hub portion 23 which is fixed on the shaft 21 as 40 shown in Figure 2.

45 Preferably the feed paddles are braced by fins 22' on their rear faces which stiffen them and prevent rearward deflection thereof. Also, if desired, these paddles may be provided with reinforcing beadings 22a along their material receiving edges.

Material is fed axially into the feed housing by a suitable lateral conveyor which will preferably comprise a usual feed auger 24 rotatably disposed in a feed trough 25 the delivery end of which 50 communicates with the feeder housing 18 through an opening 26 as illustrated in Figure 2. The lateral conveyor 24 is in axial alignment with the rotary feed element 22 and preferably the hub 55 23 of the feed element is axially extended through the trough 25 to function as a support and drive shaft for the auger 24, whereby both the 60 auger and the feed element may have a common

drive means. It will be understood that the outer or remote end of the shaft 23 will be rotatably supported in accordance with usual practice.

In accordance with my invention the rotary feed element 22 is driven in coordinated relation with the elevator conveyor 4 in such manner that the upwardly rotating paddles 22 will deliver their respective charges of material between the downwardly moving conveyor flights 5 on the return side of the conveyor and will avoid forcing incoming charges of material against the conveyor flights 5 in a manner to cause possible damage either to the conveyor flights 5 or to the feeder paddles 22. The relatively opposite movement of the paddles 22 and the conveyor flights 5 of course makes this a problem and yet such opposite movement is required by the very nature of the organization in which the respective parts are employed.

By coordinating the movements of the feed paddles 22 and the elevator conveyor 4 in accordance with the invention, the arrangement is such that each feed paddle 22 sweeps across the bottom 18a of a housing 18 to deliver its charge of material just rearwardly of one of the conveyor flights 5, and then will have been rotated upwardly through approximately 90° to have completed its feeding phase well before the next conveyor flight 5 of the return run moves downwardly abreast thereof. This can probably be best understood by reference to Figure 1 wherein the feed paddle 22 most closely adjacent the conveyor 4 has just completed feeding material behind the lowermost conveyor flight 5 and, having been rotated upwardly through approximately 90°, is commencing its movement away from the conveyor 4 as the next succeeding conveyor flight 5 moves downwardly to a position abreast thereof.

Such a coordinated relation between the rotary feed element and the elevator conveyor 4 may be established by a conventional drive chain 27 operatively disposed about sprockets 28 and 29 respectively on the shafts 3 and 21. Preferably the sprocket 29 has a multiple of the number of teeth of sprocket 28 to end that the feed element 22 may be rotated to attain a peripheral speed substantially greater than the movement of the conveyor 4, whereby the conveyor flights 5 may be spaced relatively close together and the feed paddles 22 will nevertheless function to inject a charge of material between each adjacent pair of said conveyor flights.

The sprocket 28 is fixed on its shaft 3 in usual manner, however, in the preferred embodiment of the invention the sprocket 29 constitutes a portion of a constantly rotating clutch member having dogs 30 thereon as shown in Figures 3 and 4 for operative interengagement or meshing with the dogs of a clutch member 31 which is splined or slidably keyed on the shaft 21 for movement into and out of operative engagement with clutch member 30. Preferably the interengaging dogs of the respective clutch members are formed with sloping or inclined engaging surfaces 30a, 31a respectively whereby the elements 30 and 31 may function as a slip clutch or coupling to automatically disconnect the drive to the rotary feed element 22 and also the lateral conveyor auger 24 in the event of a choking or clogging of material handled by these elements. In order that the coupling thus formed may function as a slip clutch, a spring 32 is disposed on the shaft 21 under compression between the clutch member 31 and a suitable stop which may be

defined by the washers 33 abutting against a cross-pin 34 disposed diametrically through the outer end of the shaft 21. It will be seen that such spring 32 will normally urge the clutch members 30 and 31 into operative engagement but will yield when axial pressure thereon caused by the camming action between the interengaging inclined faces 30a—31a on the clutch reaches a sufficient magnitude under overloading of the elements 22 or 24.

The dogs on the constantly rotating clutch member 30 and on the driven member 31 are arranged in the preferred embodiment to be equal in number to the respective paddles 22 and to be 15 equally angularly spaced around the axis of the shaft 21 in the same manner as the blades 22, so that these members may interengage and establish a driving connection for the feed paddles 22 in any of their several operative coordinated 20 positions. However, it is only necessary of course that the drive be operable to engage in but one coordinated position. The essential feature is that the position or positions of engagement be only those in which the positions of the feed 25 paddles 22 are properly coordinated with the relative positions of the conveyor flights 5 whereby the paddles will always feed material between the conveyors or conveyor flights 5 as aforementioned.

30 In order to permit convenient manual control of the auger 24 and the feed paddles 22, a collar 35 rotatably journaled in an annular groove around the clutch member 31, is trunnioned as at 36 to the forked or bifurcated lower end of a 35 shifting lever 37 which may be manually controlled in conventional manner to engage or disengage the clutch members 30 and 31 as desired. The lever 37 is fulcrumed at 38 on a bracket 39 on the feeder housing 18.

40 In the operation of the invention, as for instance in delivering ensilage into a silo, the ensilage may be delivered into the trough 25 from a usual farm wagon or other vehicle, preferably being delivered into the trough 25 by suitable unloading mechanism in a substantially constant flow. Such ensilage will be delivered by the auger 24 in a substantially steady flow to the paddles 22. Due to their coordinated relationship with the conveyor flights 5 the paddles 22 will feed the ensilage tangentially across the bottom 18a of the feeder housing 18 and through the opening 19 into the boot 16 on the return side of the elevator conveyor 4. It will be seen that the conveyor flights 5 on this side of the conveyor 4 are moving downwardly while the relatively adjacent feed paddles 22 are rotating upwardly, so that unless the positions and movements of these respective feed paddles 22 and conveyor flights 5 are properly coordinated, the feed paddles 22 could tend to force the ensilage upwardly against the downwardly moving conveyor flights 5 with ensuing damage to the machine. However, with such coordinated arrangement as heretofore described, each paddle 22 will feed material between adjoining pairs of conveyor flights 5 and no appreciable amount of material will ever be delivered directly against a descending conveyor flight 5.

45 The material thus delivered into the boot 16 at the lower end of the conveyor housing 3 is carried upwardly by the respective flights 5 and over the top of the U-shaped partition 12 thence is discharged into the silo through the discharge spout 17 before each conveyor flight 5 commences its return movement downwardly.

In the event material becomes jammed in the auger 24 or the feed paddles 22 the clutch members 30 and 31 may be forced axially apart against the spring 32 by the camming action of the inclined clutch or dog faces 30a-31a of these members to disengage or disconnect the drive to the elements 22 and 24 and thereby avoid damage thereto. When the drive is resumed it will be seen that the positions of the dog elements on these respective clutch members are such as to reengage only in positions wherein the locations and movements of the paddles 22 and the conveyor flights 5 are properly coordinated.

Similarly, where it is desired to discontinue the delivery of the material to the conveyor 4 this may be readily accomplished manually by actuation of the control lever 37 in usual manner. When the clutch members are manually reengaged by upward movement of the clutch lever 37 they will similarly reengage only in positions which insure the proper coordination between the feed paddles 22 and the conveyor flights 5.

In this application I have shown and described only the preferred embodiment of my invention simply by way of illustrating the preferred mode of carrying out my invention as by law required. I recognize however, that my invention may be modified in various ways and accordingly, the foregoing description and drawings are to be construed as merely exemplary in character.

I claim:

1. In an elevator a boot, a member rotatable therein, an endless conveyor having uniformly spaced flights operatively disposed around said member, a feeder housing communicating laterally with said boot on one radial side of said member, a feed element mounted in said feeder housing for rotation about an axis parallel to the rotational axis of said member, said element including a plurality of uniformly spaced feed paddles, an auger conveyor delivering material into said feed housing to be fed by said feed element to said conveyor, a common shaft rotatably supporting said feed element and said auger conveyor, means driving said endless conveyor and said feed element in coordinated relation with their respective adjoining flights and paddles moving alternately in opposite directions past the feed opening to cause the feed paddles to deliver their respective charges of material between the conveyor flights, disengageable clutch mechanism interposed between said drive means and the feed wheel, said mechanism being engageable only in one of the properly coordinated positions of said feed wheel and said endless conveyor.

2. In an elevator, a boot, a member rotatable therein, an endless conveyor having uniformly spaced flights operatively disposed around said member, a feeder housing communicating laterally with said boot on one radial side of said member, a feed element mounted in said feeder housing for rotation about an axis parallel to the rotational axis of said member, said element including a plurality of uniformly spaced feed paddles, an auger conveyor delivering material into said feed housing to be fed by said feed element to said conveyor, means driving said endless conveyor and said feed element in coordinated relation with their respective adjoining flights and paddles moving alternately in opposite directions past the feed opening, and disengageable clutch mechanism interposed between said drive means and the feed element, said mechanism being engageable only in one of the

properly coordinated positions of said feed element and said endless conveyor.

3. In an elevator, a boot having a laterally directed infeed opening, a member rotatable therein, an endless conveyor having uniformly spaced flights operatively disposed around said member, a feed element, means rotatably supporting same adjacent said conveyor for rotation about an axis parallel to the rotational axis of said member, said element including a plurality of uniformly spaced feed paddles, conveyor means delivering material to said feed element, means driving said endless conveyor and said feed element in coordinated relation with their respective adjoining flights and paddles moving alternately in opposite directions past the feed opening, and disengageable clutch mechanism interposed between said drive means and the feed element, said mechanism being engageable only in one of the properly coordinated positions of said feed element and said endless conveyor.

4. In an elevator, the combination of an endless conveyor and means operatively supporting same, said conveyor including a plurality of relatively spaced conveyor flights, a feed wheel mounted for rotation adjacent said conveyor, said wheel including a plurality of circumferentially spaced substantially radial feed paddles, means connecting said conveyor and said feed wheel for operative movement in coordinated relation with their respective adjoining flights and paddles moving alternately in opposite directions past a given point, and disengageable means in said connection operative to establish said connection only in the relatively coordinated positions of said feed wheel and said conveyor.

5. In an elevator, the combination of an endless conveyor including a plurality of relatively spaced conveyor flights, a rotary feed element mounted adjacent said conveyor with one run of said conveyor disposed in substantially tangential relationship to said element, said element including a plurality of circumferentially uniformly spaced radial feed paddles, means driving said endless conveyor and said feed element in coordinated relation with their respective flights and paddles moving alternately in opposite directions past a given point, and disengageable means in said connection operative to establish said connection only in the relatively coordinated positions of said feed wheel and said conveyor.

6. The combination of claim 5 in which the disengageable means comprises a slip clutch.

7. The combination of claim 5 in which the disengageable means comprises a slip clutch including normally intermeshing driving and driven members arranged to mesh only in the relatively coordinated positions of the feed wheel and conveyor.
